DEMOUNTABLE CHAIN

Nat Cordis, Silver Lake, Wis.

Application May 11, 1949, Serial No. 92,553

1 Claim. (Cl. 74—254)

1

This invention relates to drive and conveyor chains and more particularly to drive and conveyor chains of the type which includes links formed of a series of pairs of opposed side bars and alternate plates connected by pintles or hinge pins, some of the plates also serving to support transverse scrapers or paddles. More specifically, my invention relates to demountable conveyor chain assemblies adapted for use in barn cleaners.

The barn cleaner of the kind to which my invention relates includes a trough or gutter in the floor of the barn adjacent the animal stalls. This gutter or trough usually passes stalls on opposite sides of a barn floor and the cleaner travels in a loop. At some point along the travel of the cleaner, a pit is provided for the accumulation of refuse deposited therein as the chain and paddle pass over the pit. An elevator carries the refuse from the pit to a distributing point or vehicle and this elevator may also use the chain and paddle assembly produced in accordance with this invention. Chains for conveying the paddles through the troughs must be strong, rugged, and demountable to permit modification or repair of the assembly by unskilled labor on the site.

A desirable feature in chains of the above type is the provision of demountably fabricated chain links which are constructed so as to permit the separation of the chain at any point for lengthening or shortening the chain. In chains having this feature, however, it is necessary to provide means for locking the parts to prevent unintended separation during the normal use of the chain.

It is therefore an object of my invention to provide a chain construction which is demountable. Another object is to provide a positive means for locking the demountable chain elements. A further object of the invention is to provide a demountable chain assembly in combination with paddles or scrapers which is particularly adapted for use in barn cleaners. An additional object is to provide a method and means for fabricating and modifying a conveyor chain assembly which avoids any on-the-job welding and can be installed by unskilled labor. These and other objects of my invention will become apparent as the description thereof proceeds.

In general, I attain the objects of my invention by providing alternately arranged plate links and pairs of parallel side bars which are connected by removable hinge pins or pintles. The side bars are provided with apertured or keyhole slots and the units are assembled by relative movements of the parallel side bars and the in-

2

terposed plate link. A keeper means is removably fixed adjacent one of the side bars to retain the pintles associated with each pair of parallel side bars in spread relation and thereby prevent accidental separation of the side bars and plate links connected by said pintles. A bracket for supporting the paddle or scraper is fixed to some of the links and is welded to or is integral with the plate link. The paddle is of novel configuration and is adapted to be carried by the bracket in either of two positions, depending upon the intended direction of chain travel.

To illustrate my invention I have shown embodiments thereof in the drawings wherein:

15 Figure 1 is a top view of a portion of my chain; Figure 2 is a side view, partly in section, along the line 2—2 in Figure 1 to show the overlapping and interlocking of link elements;

20 Figures 3 and 4 are perspective views of the plate link and side bar, respectively, used in the chain;

Figures 5 and 7 are plan views of two embodiments of the keeper means;

25 Figure 6 is a section taken along the line 6—6 in Figures 5 and 7;

Figure 8 is a side view of a paddle hinged to a chain element;

Figure 9 is an end section of the assembly taken along the line 9—9 in Figure 8; and

30 Figure 10 illustrates one embodiment of a hinge pin or pintle used in the chain shown in Figures 1 and 2.

Referring to the drawings wherein corresponding elements in the various figures are designated by similar reference numerals, the chain construction includes alternate plate links 10 and pairs of parallel side bars 11 which are connected by pins 12 and secured by pin retainer or keeper means 13.

40 To fabricate the chain, a pin 12 is passed through the pin-receiving aperture or opening 14 in link 10, the aperture 14 being large enough for the heads or ends of the pin 12 to pass freely therethrough. Two side bars 11 are disposed on opposite faces of the link 10 with the pin receiving opening 15 of the apertured keyhole slot 15—16 in register with the pin 12 which passes through the link 10 at 14. Intermediate the ends of pin 12 are provided recesses 12a and 12b which accommodate the slots 16 in side bars 11. The parallel pair of side bars 11 is then slid longitudinally of the plate link 10 and the recesses 12a and 12b of the pin 12 enter the slots 16 with the heads of pin 12 abutting the outer

50 faces of the parallel side bars 11. A second link

55

10 is placed between side bars 11 with the enlarged pin receiving openings 15 and the hinge pin opening 14 in alignment. A pin 12 is passed through openings 15, 14 and 15 and then the pin 12 and the plate link 10 are slid longitudinally relative to the side bars 11 to assume the positions shown in Figures 1 and 2.

A pin retainer 13, such as that shown in Figures 5, 6, and 7 is fit snugly under the heads of pins 12 and within recess 12a as shown in Figures 1 and 2. The retainer may be flexible and is preferably coextensive with the shape of the side bars 11 and is slotted adjacent its ends to engage the recess in the pintles 12 thereby to maintain the pintles in spread position in bearing contact with the side bars at the ends of the slots 16. The depressed portions of stops 17 coincide with the enlarged openings 15 in the side bars 11 and provide positive means for locking the retainer 13 and thereby preventing accidental removal of the retainer.

The retainer illustrated in Figures 1, 2 and 5 includes pin engaging slots 18 which are parallel and extend transversely to the long axis of the side bars 11. However, it is contemplated that the slots may be disposed as shown at 19 and 20 in Figure 7. This latter embodiment is affixed to the chain in a manner similar to that described in connection with Figure 5 but the slot 19 is first placed under the head of pin 12 and then the retainer (and slot 20) are swung into position about slot 19 as a pivot until the stops 17 enter the openings 15 and lock it in place.

The pin keepers or retainers 13 are not in tension since they do not carry any of the load applied to the pins 12 but merely spread the pins to keep them in slots 16 and in bearing contact with the links and side bars which are ordinarily in tension. The retainers can therefore be made of relatively flexible metal stock such as sheets of iron, steel, aluminum, or the like.

Figures 8, 9, and 10 illustrate a barn cleaner paddle or scraper which is mounted on the chain at spaced intervals. In Figures 1 and 2 is shown the bracket 21 fixed, as by welding, to the plate link 10 and having bolt receiving opening 22. The paddle 23 is provided with a pair of corresponding slots 24 and 25 which may accommodate either bracket 21 or paddle bolt 27. By having the pair of slots, the paddle is rendered interchangeable with respect to the direction of travel of the chain assembly within the barn gutter. When installed in such gutter, the chain travels along one side thereof near the bottom and the lower edge of the paddle 23 travels in contact with the floor of the gutter. If the chain is arranged to travel clockwise, slot 24 of the paddle 23 engages the bracket 21. On the other hand, if the endless chain is driven in a counter-clockwise direction, the slot 25 of the paddle 23 engages the bracket 21 as shown in the illustrated embodiment. A paddle bolt 27 is passed through slot 24 or 25, whichever is not used to engage the bracket 21, and thence through the opening 22 in the bracket 21. A spacer element or ring 26

may be interposed between the leading edge of the paddle 23 and bracket 21 as shown in Figure 9 and a suitable nut or locking pin completes the assembly. It is also contemplated, however, that other types of paddles and paddle mounts may be used. For example, I can provide an inverted U-shaped bracket with the base fixed to the plate link and mount a wooden or metal paddle within the bracket on a bolt or pin passing through the arms of the U.

Although I have described my invention with reference to particular embodiments, this is for the purpose of illustration only and my invention is not limited thereto. For example, the paddle 23 is shown in the drawing as having a slot 25 to engage the paddle bolt 21, but in another embodiment the slot 25 can be replaced by a round hole through which the bolt 27 is passed. Likewise, the paddle mounting 21 can be curved below the upper face of the paddle 23 toward the inner face of the leading edge of the paddle and in that event spacer 26 is unnecessary. It is therefore contemplated that these and other modifications can be made by those skilled in the art without departing from the spirit of my invention described herein or as defined by the appended claim.

What I claim is:

A demountable chain comprising in combination a central plate link having a pintle-receiving bore near each end, parallel side bars, pintles passing through said bores to connect one plate link and successive pairs of parallel side bars, said side bars having opposed pairs of apertured slots through which said pintles extend, and a flexible retainer firmly but detachably mounted substantially coextensively with only one of said side bars, open slots adjacent the ends of said retainer engaging annular recesses in said pintles and maintaining said pintles in spread position in bearing contact with said side bars at remote ends of the slots therein, said retainer being further provided with integral flexible tab means engaging adjacent ends of the apertured slots of one side bar when in pintle-retaining position.
